(No Model.)

H. P. BULLOCK & H. P. CAYCE.

GATE.

No. 352,080.

Patented Nov. 2, 1886.

UNITED STATES PATENT OFFICE.

HENRY P. BULLOCK AND HENRY P. CAYCE, OF JONESBOROUGH, TEXAS.

GATE.

SPECIFICATION forming part of Letters Patent No. 352,080, dated November 2, 1886.

Application filed March 11, 1886. Serial No. 184,922. (No model.)

To all whom it may concern:

Be it known that we, HENRY P. BULLOCK and HENRY P. CAYCE, of Jonesborough, in the county of Coryell and State of Texas, have 5 invented a new and Improved Gate, of which the following is a full, clear, and exact description.

Our invention relates to gates, especially farm-gates, and has for its object to provide a simple, inexpensive, and self-closing gate which may be opened automatically by the depression of a platform in the gateway, or may be opened by the pulling of cords pendent from a support at or near the gateway.

15 The invention consists in certain novel features of construction and combinations of parts of the gate, all as hereinafter fully set forth.

Reference is to be had to the accompanying drawings, forming a part of this specification, 20 in which similar letters of reference indicate corresponding parts in both the figures.

Figure 1 is a perspective view of the gate shown closed and partly broken away and in section; and Fig. 2 is a side elevation, partly 25 broken away and drawn to a smaller scale, and shows the gate open.

Two pairs of posts, A A and B B, are set in line with the fence C, which, as shown, consists of wires, said posts being tied together 30 by horizontal bars D D, between which the gate E and its operating-levers work, and the tops of the pairs of posts are connected by cross-bars a b, respectively.

To the inner faces of the bars D D are fixed 35 a pair of opposite shorter rails or track-bars, d, on which the opposite top rails, f f, of the gate F run, and between the inner ends of the rails f f there is fixed an arm, G, to which are pivoted at g the outer ends of a pair of bars 40 or links, H, the inner ends of which are pivoted at h to the diagonally-ranging lever, I, which is pivoted at its lower end by a pin, i, and between the posts B B.

At a point below the pivot h the lever I is 45 pivoted at j to and between a pair of upright movable bars, J J, which are held to each other by bolts passed through them and through a spacing-block, j', which is a little thicker than the lever I, and to and between 50 the lower ends of the bars J J is pivoted at k the inner end of a lever, K, which passes outward between the posts A A and is fulcrumed

thereto on a pin, k'. The outer end, k², of the lever K is arranged in such relation to the opposite platforms, L L, which lie across the gateway, that when either platform is depressed by a passing vehicle the lever will be lowered thereby and the inner end of the lever will be raised, whereby the lever I will be swung over backward as the bars J J are lifted, and the 60 gate F will be drawn backward between the posts A A or opened, as indicated in Fig. 2, and as soon as the depressing weight is taken from the platforms L the weight of the parts I J H on the inner end of lever K will cause 65 the gate to close automatically.

If desired, a spring, M, may be arranged between the rear posts, B, and the bars J or lever I, to insure or assist the closing of the gate.

To make the weight of the gate F available 70 to assist in closing it, a pin, N, may be passed through holes n n, made in the links H and bar G, to hold them in line, whereby, when the gate is thrown backward to open it, it will be lifted from the tops of the supporting track-bars d, and will rest on the upper forward corners of said bars, as indicated in dotted lines 75 in Fig. 2; hence the lifted open gate will easily slide over the ends of bars d as it falls by gravity to a horizontal position in closing. 80

To allow the gate to be opened by persons on horseback from either side, a rope, O, is connected at one end to the upper end of the lever I, and thence passed to and over a pulley or sheave, P, journaled to the top of posts B B, 85 and thence forward to where it connects at o with the two cords R S, which extend over the top of the head-piece a of posts A A, and hang therefrom within reach of the rider. Pins r r and s s, fixed in the head-piece a, hold the 90 cords R S in proper positions, so that they cannot be pulled off the head-piece.

The post T, at the farther side of the gateway, may be provided with pairs of blocks t t, between which the end of the closed gate 95 may rest to prevent sidewise racking of the gate.

A series of holes may be made in the gate-posts A A, as at a', to receive the fulcrum-pin k' of the lever K, for giving a greater or less 100 throw to the gate in opening it, and a pin, U, may be passed through holes u, made in the gate and behind the posts A, to hold the gate open when it may be desirable or necessary,

as will be understood from Fig. 2 of the drawings.

The gate will not sag to the ground, and will not freeze up easily, and is inexpensive to make and to set up along railroads or on farms, or in other localities where a gate of this character would be useful.

Having thus fully described our invention, we claim as new and desire to secure by Letters Patent—

1. The combination of the gate F, front and rear posts, A B, lever K, pivoted between its ends to the lower ends of the front posts, a vertically-movable platform, L, in the gateway, adapted to operate the front end of the lever K, bars J, connected at the lower ends to the rear end of lever K, a forwardly-inclined lever, I, pivoted at its lower end to the lower ends of the rear posts and at j to the bars J, and links H, pivotally connecting the gate and the lever I above the point j, substantially as set forth.

2. The combination, with the gate F, forwardly-inclined lever I, having a pivotal connection therewith, vertical bars J, pivoted between their ends to the said lever, and links H, connecting the lever I to the gate above the point of connection with bars J, of the spring M, acting between the rear posts and

the lever I, and means for moving the said lever and bars upward against the action of the spring, substantially as set forth.

3. The combination, with the gate F, front and rear posts, A B, forwardly-inclined lever I, pivoted at its lower end to the rear posts, 35 and links H, connected to the inner end of the gate and to the lever I between its ends, of the cord O, connected to the upper end of lever I, the guide-pulley P at the upper ends of the rear posts, over which the cord passes, and 40 cords R S, connected to the end of cord O, and pendent from a head-piece, a, on the front posts, substantially as set forth.

4. The combination, with the gate F, forwardly-inclined lever I, pivoted at its lower 45 end to the rear gate-posts, and links H, pivoted to the rear end of the gate and to the lever between its ends, of a pin, N, passed through holes in the links H beyond their pivotal points and through a bar fixed to the rear 50 end of the gate, substantially as set forth, whereby the gate will be lifted as it is opened.

HENRY P. BULLOCK.

HENRY P. CAYCE.
